Primary Examiner — Karen S Acker**CLAIM**

The ornamental design for an air mattress, as shown and described.

DESCRIPTION

FIG. 1 is a perspective view of an air mattress showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines and areas within depict portions of the air mattress that form no part of the claimed design. The dot dash dot broken line in FIG. 3 denotes the boundaries of the claim and forms no part of thereof.

1 Claim, 7 Drawing Sheets(56)
